(57) **CLAIM**

We claim, the ornamental design for a confectionery packaging, as shown and described.

DESCRIPTION

FIG. 1 is a perspective view of a confectionery packaging, showing our new design in a first embodiment; FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1; FIG. 6 is a top view of the embodiment shown in FIG. 1; FIG. 7 is a bottom view of the embodiment shown in FIG. 1; FIG. 8 is a cross-sectional view of the embodiment shown in FIG. 1 as taken along line **8-8** of FIG. 6; FIG. 9 is a perspective view of a confectionery packaging, showing our new design in a second embodiment; FIG. 10 is a front view of the embodiment shown in FIG. 9; FIG. 11 is a rear view of the embodiment shown in FIG. 9; FIG. 12 is a side view of the embodiment shown in FIG. 9; FIG. 13 is another side view of the embodiment shown in FIG. 9; FIG. 14 is a top view of the embodiment shown in FIG. 9; FIG. 15 is a bottom view of the embodiment shown in FIG. 9; FIG. 16 is a cross-sectional view of the embodiment shown in FIG. 9 as taken along line **16-16** of FIG. 14; FIG. 17 is a perspective view of a confectionery packaging, showing our new design in a third embodiment; FIG. 18 is a front view of the embodiment shown in FIG. 17; FIG. 19 is a rear view of the embodiment shown in FIG. 17; FIG. 20 is a side view of the embodiment shown in FIG. 17; FIG. 21 is another side view of the embodiment shown in FIG. 17; FIG. 22 is a top view of the embodiment shown in FIG. 17; FIG. 23 is a bottom view of the embodiment shown in FIG. 17;

(Continued)

FIG. 24 is a cross-sectional view of the embodiment shown in FIG. 17 as taken along line 24-24 of FIG. 22; FIG. 25 is a perspective view of a confectionary packaging, showing our new design in a fourth embodiment; FIG. 26 is a front view of the embodiment shown in FIG. 25; FIG. 27 is a rear view of the embodiment shown in FIG. 25; FIG. 28 is a side view of the embodiment shown in FIG. 25; FIG. 29 is another side view of the embodiment shown in FIG. 25; FIG. 30 is a top view of the embodiment shown in FIG. 25; FIG. 31 is a bottom view of the embodiment shown in FIG. 25; and, FIG. 32 is a cross-sectional view of the embodiment shown in FIG. 25 as taken along line 32-32 of FIG. 30. The broken line disclosure forms no part of the claimed design.
